UNITED STATES PATENT OFFICE

154,514

DESIGN FOR A BOTTLE POURER

Robert L. Schneider, San Francisco, Calif.

Application July 13, 1946, Serial No. 131,556

Term of patent 14 years

(Cl. D58—10)

To all whom it may concern:

Be it known that I, Robert L. Schneider, a citizen of the United States of America, residing at the city and county of San Francisco and State of California, have invented a new, original, and ornamental Design for a Bottle Pourer, of which the following is a specification, reference being had to the accompanying drawings, forming part thereof.

Fig. 1 is a side view of the bottle pourer, showing my new design. Both sides are identical in appearance.

Fig. 2 is a top plan view of the device.

Fig. 3 is a bottom plan view of the device.

I claim:

The ornamental design for a bottle pourer, as shown and described.

ROBERT L. SCHNEIDER.
